(57) **CLAIM**

We claim the ornamental design for an electric bicycle, as shown and described.

DESCRIPTION

FIG. 1 is a rear and left side perspective view of an electric bicycle embodying our new design;

FIG. 2 is a front and left side perspective view thereof;

FIG. 3 is a rear and right side perspective view thereof;

FIG. 4 is a front and right side perspective view thereof;

FIG. 5 is a right side elevation view thereof;

FIG. 6 is a left side elevation view thereof;

FIG. 7 is a front elevation view thereof;

FIG. 8 is a rear elevation view thereof; and,

FIG. 9 is a top plan view thereof.

The broken lines in the drawings illustrate portions of the electric bicycle that form no part of the claimed design.

1 Claim, 9 Drawing Sheets
